MECHANISM FOR STRIPE COATING
ARTICLES

William P. Winters, Cincinnati, Ohio, and William Pechy, Belmar, N. J., assignors to American Can Company, New York, N. Y., a corporation of New Jersey

Application July 24, 1951, Serial No. 238,204

5 Claims. (Cl. 118—2)

1

The present invention relates to a mechanism for stripe coating the outer surface of articles, such as containers and container bodies and has particular reference to devices for shielding the spaces between such articles moving in a substantially continuous procession.

An object of the instant invention is the provision of such a mechanism wherein a continuously operating spray may be utilized to apply a stripe of coating material to a plurality of articles moving in spaced and timed order in a substantially continuous procession, the spaces between the articles being shielded to prevent the spray from contacting the ends of closed articles and the interior of articles with open ends.

Another object is the provision of such a mechanism wherein the shielding of the spaces between the articles in the procession is effected by a rotatable flat disc having imperforate portions which coincide with and block off the spaces between the articles.

Another object is the provision of such a mechanism wherein the spray of coating material may be entirely diverted from the path of travel of the articles when there are no articles present to receive the coating material.

Another object is the provision of such a mechanism wherein the coating device is enclosed in such a manner as to collect and drain away all unused coating material so that adjacent parts of the mechanism may be kept free and clear of this unused coating material.

Numerous other objects and advantages of the invention will be apparent as it is better understood from the following description, which, taken in connection with the accompanying drawings, discloses a preferred embodiment thereof.

Referring to the drawings:

Figure 1 is a top plan view of a portion of a machine including the stripe coating mechanism embodying the instant invention, with parts broken away;

Fig. 2 is a fragmentary sectional view taken substantially along the line 2—2 in Fig. 1;

Fig. 3 is a transverse sectional view taken substantially along the line 3—3 in Fig. 1, with parts broken away;

Fig. 4 is a fragmentary plan view of a structural detail as taken substantially along the line 4—4 in Fig. 3; and

Fig. 5 is a perspective schematic view of principal control parts of the mechanism and a wiring diagram of electric apparatus associated with these parts.

2

As a preferred or exemplary embodiment of the invention the drawings disclose a stripe coating mechanism A (Figs. 1 and 3) for applying a stripe of coating material, such as lacquer or the like to the outer surface of soldered side seams B of open end sheet metal can bodies C, moving in spaced and timed order in a substantially continuous procession through a side seam soldering machine D such as the machine shown in United States Patent 1,338,716, issued May 4, 1920, to M. E. Widell, on Soldering Machine, although the invention is equally well adapted to other articles and machines, and to various kinds of coating materials.

10 In the soldering machine D, the can bodies C move along a straight line path of travel in a horizontal position and in end-to-end relation with substantially equal spaces E between the ends of the bodies, the side seams B being on the under side of the bodies and in longitudinal alignment. The bodies are supported and guided along this straight line path of travel by an outside horn or horse comprising a pair of spaced and parallel lower rods 11 and a similarly disposed pair of upper rails 12 which extend longitudinally of the machine. These rods 11 and rails 12 are secured to overhanging arms 13 which are disposed at spaced intervals and which are fastened to a composite frame structure which constitutes the main frame of the machine and which is indicated generally by the numeral 14.

15 Advancement of the can bodies C along the rods 11 and rails 12 preferably is effected by an endless chain conveyor 16 having spaced gripper dogs 17 of the character disclosed in the above mentioned Widell Patent 1,338,716. This conveyor 16 extends in a horizontal position longitudinally of the soldering machine between the upper support and guide rails 12 and operates over a driving sprocket 18 located at one end of the machine. The sprocket 18 is mounted on and rotates with a driving shaft 19 journaled in a pair of spaced bearings 21 formed in a bracket 22 secured to the main frame structure 14. The driving shaft 19 is continuously rotated by an endless chain 24 which operates over a sprocket 25 secured to the driving shaft 19 and over a sprocket 26 secured to an auxiliary driving shaft 27 journaled in a pair of spaced bearings 28 formed in the main frame structure 14. The auxiliary driving shaft 27 may be actuated in any suitable manner in time with the other moving parts of the machine, preferably as disclosed in the above mentioned Widell patent.

20 The stripe coating mechanism A is disposed

adjacent the lower support and guide rods 11 and includes an annular housing or drain pan 31 comprising a horizontally disposed bottom wall 32, an outer upright peripheral wall 33 and an inner upright wall 34 in spaced relation to the outer wall 33 and setting off between these upright walls, a drain reservoir 35. The top of the housing is open. This housing 31 is disposed in concentricity with a vertical bearing 36 of the main frame structure 14 and is secured to the bearing to maintain the housing stationary.

A portion of the drain reservoir 35 of the housing 31 extends under the can body support and guide rails 11 and encloses (excepting at the top) a conventional commercial liquid spray nozzle 38 secured in the bottom wall 32 of the housing as shown in Fig. 3. The nozzle is disposed in an upright position and at its upper end is provided with a discharge orifice 39 (Figs. 3 and 4) located below and in vertical alignment with the path of travel of the side seams B of the can bodies C for spraying a stripe of coating material onto the seams of the bodies moving in the procession supported and guided by the rods 11 and rails 12. The nozzle 38 is provided with the usual liquid and air tubes 41, 42 (Fig. 3) which lead to suitable sources of the coating material to be sprayed onto the can bodies and the air pressure to produce the desired spray. The spray is discharged from the nozzle continuously.

Control of the spray issuing from the nozzle 38 to prevent projecting the spray upwardly into the spaces E between the can bodies C moving across the nozzle preferably is effected by a rotatable flat, circular disc 45 which is disposed in a horizontal position between the support and guide rods 11 and the nozzle 38. The disc 45 is provided with a plurality of curved or arcuate elongated segmental slots 46 of a predetermined width and length and arranged in a circle concentric with the center of the disc. The width of the slots 46 is such as to restrict the width of the spray passing through them so that a stripe of a predetermined width will be applied to the side seams B of the can bodies. The length of the slots 46 preferably is equal to the length of the seams to be sprayed and the distance between the ends of the slots, which may be termed imperforate blocking or shielding or bridge sections 47 in the disc, preferably is equal to the length of the spaces E between the can bodies C in the moving procession.

The disc 45 is rotated in time with the advancement of the can bodies along the support and guiding rods 11 and rails 12, i.e. in time with the travel of the conveyor 16. For this purpose the disc 45 is disposed in the open top of the drain pan 31 within the outer peripheral wall 33, and is secured to and rotated by a vertical disc shaft 51. The disc shaft 51 is journaled in the bearing 36 and a lower spaced bearing 52 formed on the main frame structure 14. The disc shaft 51 is rotated continuously by a bevel gear 53 which is mounted on the shaft between the bearings 36, 52. This bevel gear 53 meshes with and is driven by a bevel gear 54 which is mounted on the auxiliary drive shaft 27 which drives the conveyor 16. Thus the conveyor and the disc are operated in timed relation.

As the disc 45 rotates in time with the advancement of the can bodies along the support and guide rods 11 and rails 12, the slots 46 in the disc rotate into position over the spray nozzle 38 and permit the spray from the nozzle

to pass through the slots and adhere to the side seams 8 of the passing can bodies C. The disc 45 is so timed with the conveyor 16 that the leading or forward end of a slot 46 as it approaches the nozzle, aligns with the leading or forward end of the side seam of a can body to be sprayed as shown in Fig. 1 so that spraying of the seam begins at the extreme leading end of the seam. In a similar manner the following or back end of a slot 46 as it moves away from the nozzle, moves out of alignment with the following or back end of a sprayed can body as shown in Fig. 1 so that the spraying of the seam is terminated at the extreme back end of the seam. Thus the slots 46 expose the entire length of the seams of the can bodies to the spray from the nozzle 38 and the entire length of the seams is thus sprayed with the coating material.

As the following or back end of a slot 46 passes over the nozzle 38, an imperforate bridge section 47 of the disc comes into place over the nozzle and thus blocks off or shields the space E between the ends of adjacent can bodies moving in the procession and thus prevents the spray of coating material from being projected up into space between the bodies. This prevents the coating material from being deposited inside the open can bodies and from adhering to adjacent parts of the machine. Instead, the spray is projected against the under or bottom surface of the disc and falls into the reservoir 35 where it collects and is drained away through a drain pipe 56 (Fig. 3) secured in the bottom wall 32 of the drain pan 31. This pipe may lead to the source of supply of the coating material to conserve the unused material collected in the reservoir.

In order to keep the disc 45 free of excess coating material a pair of scrapers or blades 57, 58 are used to clean the disc as the disc rotates. The scraper 57 is disposed across and in engagement with the top or outer face of the disc (see Figs. 1 and 2) while the scraper 58 is disposed across and in engagement with the lower or inner face of the disc. These scrapers are arranged at a slight receding angle relative to the radius of the disc so that the scraped-off material will flow toward the outer edge of the disc and fall into the reservoir 35 by way of an offset section 59 formed in the outer peripheral wall 33 of the drain pan 31. The outer ends of the scrapers are secured to the outer wall of this offset section 59 to hold the scrapers in place.

Provision is made for shielding the nozzle orifice 39 when no can body is in place to receive the coating material as a slot 46 of the disc 45 passes over the nozzle 38. This confines the spray to the reservoir 35 and prevents the spray from passing up through the passing slot 46. For this purpose a curved auxiliary shield or cover plate 61 (Figs. 3 and 4) is provided within the reservoir 35 and adjacent the upper end of the nozzle. The auxiliary shield 61 is movable horizontally across the top of the nozzle to cover its orifice and for this purpose is mounted on the inner end of a horizontal rod 62 slideably carried in a bearing 63 formed in the outer peripheral wall 33 of the drain pan 31. The outer end of the rod is connected to an upright arm 64 of a bell crank lever 65 mounted on a pivot pin 66 carried in the main frame structure 14. A lower arm 67 of the bell crank lever 65 is connected to a movable core 68 of an electric solenoid 69.

The solenoid 69 (see Fig. 5) is connected by

wires 71, 72, 73 to a normally closed electric switch 74 disposed adjacent the can body support and guiding rods and rails 11, 12 and to a source of electric current such as a generator 75. The switch 74 is controlled by a leg 76 of a detector finger 77 (see also Fig. 1) mounted on a pivot pin 78 secured in the main frame structure 14. The detector finger 77 is disposed in the region of the spray nozzle 38 and extends along the path of travel of the can bodies moving along the support and guide rods and rails 11, 12 so as to be engaged by the outer surfaces of the bodies. The length of the finger 77 is slightly greater than the space E between the bodies so that the finger bridges this space. A tension spring 81 (Fig. 1) between the leg 76 of the finger and the casing of the switch 74 forces the finger 77 toward and into engagement with the moving can bodies.

As long as the procession of can bodies advancing along the horn is substantially continuous, i. e. with each can body in place in properly spaced order, the bodies engage the detector finger and hold it in the position shown in Fig. 1 in which position it maintains the switch 74 in its normally closed condition. With the switch 74 closed, electric current passes from the generator 75 along the wires 71, 72, 73 and the closed switch 74 and thus energizes the solenoid 69. The energized solenoid 69, through the bell crank lever 65 holds the auxiliary shield 61 in a retracted position away from the nozzle 38 as shown in Figs. 3 and 4, against the resistance of a tension spring 82 (Fig. 3) stretched between the bell crank 65 and the drain pan 31. Thus the nozzle 38, in conjunction with the disc 45 is permitted to deposit the stripe of coating material onto the side seams B of the passing can bodies C as described above.

When one or more can bodies C are missing in the procession passing along the horn, the tension spring 81 of the detector finger 77 immediately rocks the finger into the path of travel of the bodies in the space made by the missing body or bodies. This inward rocking of the detector finger 77 causes its leg 76 to open the switch 74. The opening of the switch breaks the electric circuit from the generator 75 and thus de-energizes the solenoid 69. The tension spring 82 connected to the bell crank lever 65 thereupon rocks the bell crank lever toward the drain pan 31 and this pushes the rod 62 inwardly and moves the auxiliary shield 61 into a position over the nozzle 38 so that it catches the spray issuing from the nozzle orifice 39 and diverts it back into the reservoir 35, unused. Thus, while the disc 45 continues to rotate, the spray from the nozzle is prevented from being projected up through the disc slots 46.

When the next can body C, after the space made by the missing body or bodies in the procession, advances into position for spraying it engages the detector finger 77 and pushes it outwardly into its normal position as shown in Fig. 1. This outward rocking of the finger, recloses the switch 74, re-establishes the electric circuit which re-energizes the solenoid 69 and thus through the bell crank 65, withdraws the auxiliary shield 61 and permits the nozzle 38 to again perform its function of spraying the can body when it aligns with the slot 46 in the disc 45.

It is thought that the invention and many of its attendant advantages will be understood from the foregoing description, and it will be apparent that various changes may be made in the form, construction and arrangement of the parts with-

out departing from the spirit and scope of the invention or sacrificing all of its material advantages, the form hereinbefore described being merely a preferred embodiment thereof.

We claim:

1. In a machine for stripe coating the outer surfaces of articles, the combination of a support for a plurality of articles, means for moving said articles along said support in spaced processional order; a circular drain pan disposed beneath said support; a nozzle disposed in said drain pan adjacent the path of travel of said articles for projecting a spray of coating material onto the outer surface of each of said moving articles; a flat circular disc rotatably mounted in said drain pan and in concentricity with and covering the open top thereof, said disc being interposed between said support and said nozzle and having alternate elongated arcuate openings and imperforate sections proportioned and corresponding, respectively, to the length of said articles and the spaces therebetween; means for rotating said disc member in time with said means for moving the articles along said support to permit passage of said spray from the nozzle to said articles during passage of said articles adjacent the nozzle and to intercept said spray during the passage of said spaces between articles adjacent the nozzle; a shield disposed adjacent said nozzle and movable into a position over the nozzle to intercept and divert said projected spray; means for detecting the absence of an article in the procession passing said nozzle; and means controlled by said detecting means for moving said shield into the path of said spray and thus prevent it from being projected into the path of the moving articles while a said opening in the disc, corresponding to the vacant article space in the procession, moves over the nozzle.
2. In a mechanism for stripe coating the outer surfaces of articles, the combination of a support for a plurality of articles, means for moving the articles along said support in spaced professional order; a nozzle disposed adjacent the path of travel of said articles for projecting a spray of coating material onto the outer surface of each of said moving articles; a flat disc interposed between said support and said nozzle, said disc having alternate elongated arcuate openings and imperforate sections proportioned and corresponding, respectively, to the length of said articles and the spaces therebetween; means for rotating said disc member in time with said means for moving the articles along said support to permit passage of said spray from the nozzle to said articles during passage of said articles adjacent the nozzle and to intercept said spray during passage of said space between articles adjacent the nozzle; a shield disposed adjacent said nozzle and movable into a position over the nozzle to intercept and divert said projected spray; means for detecting the absence of an article in the procession passing said nozzle; and means controlled by said detecting means for moving said shield into the path of said spray to divert the spray and thus prevent it from being projected into the path of the moving articles while a said opening in the disc, corresponding to the vacant article space in the procession, moves over the nozzle.
3. In a mechanism for stripe coating the outer surfaces of articles, the combination of a support for a plurality of articles; means for moving the articles along said support in spaced processional order; a nozzle disposed adjacent the path of

travel of said articles for projecting a spray of coating material onto the outer surface of each of said moving articles; a rotating flat disc interposed between said support and said nozzle, said disc having alternate elongated arcuate openings and imperforate sections proportioned and corresponding, respectively, to the length of said articles and the spaces therebetween; means for rotating said disc member in time with said means for moving the articles along said support to permit passage of said spray from the nozzle to said articles during passage of said articles adjacent the nozzle and to intercept said spray during passage of said spaces between articles adjacent the nozzle; a detecting finger having a longitudinal surface engageable with each of said articles and longer than a said space between the articles for spanning said space and thus maintaining continuous engagement of said surface with at least one article during an uninterrupted procession of the articles; a shield movable into a position over said nozzle to intercept and divert the projected spray; and means controlled by said detecting finger, when said finger is momentarily disengaged from contact with any article due to the absence of an article from said procession, for moving said shield into position over said nozzle to divert the spray and thus prevent it from being projected into the path of the moving articles while a said opening in the disc, corresponding to the vacant article space in the procession, moves across the nozzle.

4. In a mechanism for stripe coating the outer surfaces of articles, the combination of a support for a plurality of articles; means for moving the articles along said support in spaced processional order; a nozzle disposed adjacent the path of travel of said articles for projecting a spray of coating material onto the outer surface of each of said moving articles; a rotating flat disc interposed between said support and said nozzle, said disc having alternate elongated arcuate openings and imperforate sections proportioned and corresponding, respectively, to the length of said articles and the spaces therebetween; means for rotating said disc member in time with said means for moving the articles along said support to permit passage of said spray from the nozzle to said articles during passage of said articles adjacent the nozzle and to intercept said spray during the passage of said spaces between articles adjacent the nozzle; a detecting finger disposed adjacent the path of travel of said articles and in engagement with said articles; a shield movable into a position over said nozzle to intercept and divert the projected spray; means for moving said shield into said intercepting and diverting position; and electric means interposed

between said finger and said shield moving means and controlling by said detecting finger, when said finger is momentarily disengaged from contact with any article due to the absence of an article from said procession, for setting said shield moving means in operation to shift the shield into position over said nozzle to divert the spray and thus prevent it from being projected into the path of the moving articles while a said opening in the disc, corresponding to the vacant article space in the procession, moves across the nozzle.

5. In a machine for stripe coating the outer surfaces of articles, the combination of a support for a plurality of articles; means for moving said articles along said support in spaced processional order; a nozzle disposed adjacent the path of travel of said articles for projecting coating material onto the outer surface of each of said moving articles; a rotating flat disc disposed between said support and said nozzle, said disc having alternate elongated arcuate openings and imperforate sections proportioned and corresponding, respectively, to the length of said articles and the spaces therebetween; means for rotating said disc member in time with said means for moving the articles along said support to permit passage of said spray from the nozzle to said articles during passage of said articles adjacent the nozzle and to intercept said spray during passage of said spaces between articles adjacent the nozzle; a concave deflecting shield mounted for reciprocation adjacent said nozzle; actuating means for reciprocating said shield toward and away from said nozzle; and detector means controlled by the articles moving along said support for setting said actuating means in operation to shift said concave shield into position over said nozzle, when an article is missing from said procession, to divert the spray and thus prevent the spray from being projected into the path of the articles while a said opening in the disc, corresponding to a vacant article space in said procession, moves over the nozzle.
